UNITED STATES PATENT OFFICE.

WILLIAM HELMER, OF BOSTON, MASSACHUSETTS, ASSIGNOR TO THE AMERICAN SODA-FOUNTAIN COMPANY, OF SAME PLACE.

DESIGN FOR A SYRUP-CAN.

SPECIFICATION forming part of Design No. 25,856, dated August 4, 1896.

Application filed June 11, 1896. Serial No. 595,224. Term of patent 14 years.

To all whom it may concern:

Be it known that I, WILLIAM HELMER, a citizen of the United States, residing at Boston, in the county of Suffolk and State of Massachusetts, have invented and produced a new and original Design for Syrup-Cans for Soda-Water Apparatus, of which the following is a specification, reference being had to the accompanying drawings, illustrating my design, in which—

Figure 1 is a perspective view of a syrup-can, showing my design. Fig. 2 is a horizontal section of the same.

My invention relates to a design for upright syrup-cans for soda-water apparatus; and it consists in the general configuration of the article, as will be hereinafter more particularly described.

The upright syrup-can A illustrated in the accompanying drawings is intended for use in a soda-water-dispensing apparatus and is

of approximately triangular shape in cross-section, as shown in Fig. 2, its front side *a* being flat or straight throughout its entire area. The other two sides, *b c*, are brought together at *d*, the corner thus formed being preferably rounded, as shown. The side or surface *b* is of convex form, while the side or surface *c* is of concave form, as shown, the whole presenting a unique and attractive appearance.

What I claim as new, and desire to secure by Letters Patent, is—

The design for a syrup-can for soda-water apparatus, substantially as herein shown and described.

Witness my hand this 9th day of June, A. D. 1896.

WILLIAM HELMER.

In presence of—

P. E. TESCHEMACHER,
JOHN MACKSEY.
